(57) **CLAIM**

The ornamental design for a dual hitch shackle and hook assembly, as shown and described.

DESCRIPTION

FIG. 1 is a perspective view of the dual hitch shackle and hook assembly, showing my new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken lines in the figures are included for the purpose of illustrating portions of the dual hitch shackle and hook assembly and form no part of the claimed design.

1 Claim, 6 Drawing Sheets
